[57] CLAIM

The ornamental design for a semiconductor, as shown and described.

DESCRIPTION

FIG. 1 is a right side, top and front perspective view of a semiconductor showing our new design;

FIG. 2 is a rear elevational view thereof;

FIG. 3 is a left side view thereof;

FIG. 4 is a bottom view thereof;

FIG. 5 is a right side, top and front perspective view of a semiconductor showing another embodiment of our new design;

FIG. 6 is a bottom view thereof;

FIG. 7 is a right side, top and front perspective view of a semiconductor showing another embodiment of our new design;

FIG. 8 is a bottom view thereof;

FIG. 9 is a right side, top and front perspective view of a semiconductor showing another embodiment of our new design;

FIG. 10 is a bottom view thereof;

FIG. 11 is a right side, top and front perspective view of a semiconductor showing another embodiment of our new design;

FIG. 12 is a bottom view thereof.
